INTERLOCKING SWITCH STRUCTURE FOR
ELECTRICALLY OPERATED VALVES

Cyril Charles Young, Kansas City, Mo.

Application July 14, 1949, Serial No. 104,708

2 Claims. (Cl. 236—1)

1

This invention relates generally to an electrical switch and more particularly to a novel and improved interlocking switch structure for an electrically operated valve whereby the valve may be interlocked electrically in a control system circuit. It may be noted that the present invention finds a particularly useful application when used on valves employed in a control system for a combination oil and gas burner unit whereby the interlocking switch arrangement precludes concurrent operation of both a main gas valve and an oil valve.

In my copending application United States Serial No. 47,319, filed September 11, 1948, now Patent No. 2,547,611, there is disclosed and claimed a novel combination gas and oil burner and control therefor which will permit a heating plant to be efficiently operated either by an oil fuel or by a gas fuel. This type of burner unit has the advantage that for moderate outdoor temperatures, the heating of the building or residence in which the unit is installed may be accomplished solely by a gas fuel, or upon the occurrence of extreme weather conditions, the unit may be operated to burn an oil fuel to adequately supply the required amount of heat without constituting an excessive demand upon the city gas supply.

The present application specifically relates to certain structural improvements in an electrically operated valve incorporated in the control system disclosed in the acknowledged copending application.

It is an object of this invention to provide an improved electrically operated valve which may be readily incorporated in a combination oil and gas heater system and interlocked electrically in a control circuit so as to preclude simultaneous opening of a plurality of valves.

Another object of this invention is to provide an interlocking switch structure for an electrically operated valve which takes the form of an unusually simplified arrangement whereby a plurality of electrically operated valves may be interlocked in a control circuit associated therewith.

According to the general features of the present invention, an interlocking switch structure is provided having a switch support secured to the valve body of an electrically operated valve. A contact board made of electrically non-conductive material is mounted on the support and carries a first switch contact thereon. An insulator spacer is also mounted on the contact board and carries a flexible switch contact blade there-

on with a portion thereof normally contacting the first switch contact. A tab of electrically non-conductive material projects from the free end of the switch contact blade in cooperative driving relationship with a portion of a plunger type valve stem embodied in the electrically operated valve. Appropriate lead terminals are provided on the contact board which are electrically connected to the switch contacts, whereby the valve may be electrically interlocked in an appropriate control circuit leading to a second electrically operated valve.

Many other features, advantages and objects of the present invention will become manifest to those versed in the art upon making reference to the detailed description which follows and the annexed sheets of drawings in which:

Figure 1 is a schematic diagram of an electrical control system for a combination gas and oil burner embodying an electrically operated valve in accordance with this invention;

Figure 2 is a plan view partly broken away and with parts in section showing an electrically operated valve in accordance with this invention; and

Figure 3 is a cross-sectional view with parts in elevation taken on line III—III of Figure 2.

As shown on the drawings:

Although the present invention relates to structural improvements in an electrically operated valve, it is believed that a particularly clear understanding of the invention may be had by considering the application of the principles embodied therein with respect to the control circuit of a combination gas and oil burner unit.

Accordingly, although not specifically limited thereto, the present invention will be described in connection with its adaptation to such an environment.

As is more clearly set forth in my acknowledged copending application, a combination gas and oil burner unit may be provided with a blower 10 driven by an electrical motor 11 for supplying adequate amounts of air necessary to support combustion when the burner unit is operated on an oil cycle.

The combination gas and oil burner unit effects the conditioning of fuel oil for proper combustion by vaporizing the fuel oil in a high temperature zone produced by a gas fired vaporizer burner. The vaporizer burner is provided with a gas fuel which is supplied under the control of an electrically operated vaporizer gas valve 12. The main supply of fuel oil supplied for combustion in the combination oil and gas burner

unit is controlled by an electrically operated oil valve 13. The supply of gas fuel for the main gas burner of the combined gas and oil burner unit is controlled by an electrically operated gas valve 14.

The initiation of operation of the combined gas and oil burner unit on either a gas burning or an oil burning cycle may be automatically controlled in any desired manner and details of a particular arrangement for cycle selection are explained in greater detail in my copending application Serial No. 764,698, filed July 30, 1947, now Patent No. 2,552,302.

The cycle selection arrangement shown in Figure 1 corresponds identically to that disclosed in the acknowledged copending application Serial No. 764,698, whereby selection of the gas or oil burning cycle is controlled by an outdoor thermostat 16 and the intermittent operation of the combination gas and oil burner unit on the selected cycle is controlled by a room thermostat 17.

The control circuit may be operated from any suitable source of power indicated as line terminals L₁ and L₂ and, if such source is of the alternating current type, may be stepped down to a suitable voltage by a transformer 18.

The outdoor thermostat 16 is preferably of the snap-action type wherein a switch blade 16a of the thermostat selectively engages either the contact G or a contact O depending upon whether or not the outside temperature is above or below a predetermined value. For purposes of illustration, it is assumed that the outdoor thermostat 16 will have its switch blade 16a rest across its neutral terminal N to the terminal G for all outdoor temperatures above a predetermined value and will have the switch blades 16a rest across the neutral terminal N and the terminal O for all outdoor temperatures below such a predetermined value. The shifting of the switch blades 16a between the terminal G and the terminal O then effects the operation of the burner unit respectively on its gas and its oil burning cycle.

The indoor thermostats 17 may be of a conventional type and is illustrated as comprising a thermostat of the three-wire type, including a heating element 17a and a pair of contacts 17b which are closed whenever the room temperature is below a predetermined value and which are open whenever the room temperature exceeds a predetermined value.

The vaporizer gas valve 12 may be of any conventional electrically operated construction and for illustrative purposes may be considered as a solenoid controlled type valve.

According to the present invention, the main gas valve 14 takes the form of a conventional plunger type valve including a body 19 defining an apertured seat 19a through which a fluid such as a gas fuel may flow.

A leather disk washer 20 which is supported and positioned by a seat washer retaining screw 21 threadedly engageable with a valve disk and swivel assembly controls the aperture in the seat 19a.

According to conventional practice, the main gas valve 14 may be provided with an upper seat 22 and a diaphragm stem seal 23. A plunger type valve stem 24 passes through the diaphragm stem seal 23 and threadedly receives the valve disk and swivel assembly.

The operating mechanism for the electrically operated main gas valve 14 is contained within a housing 26 which may be integrated with a collar 27 by means of fasteners 28. The collar

27, in turn, is attachable to the body 19 of the valve.

An upper portion of the collar 27 is suitably formed so as to define an internally threaded bore 5 for receiving a generally cylindrical permanent magnet 29 appropriately constructed so as to freely pass the valve stem 24 therethrough.

The valve stem 24 is provided with a circular armature portion 30 which is arranged in proximity to the permanent magnet 29. The valve is normally held closed by the downward pull of the permanent magnet 29 on the circular armature 30 attached to the valve stem 24.

The main gas valve 14 is a direct operated snap-acting valve and is actuated by a bi-metal strip motor 31. The motor 31 may be heated by a low voltage heater element indicated at 31a. When a low voltage current passes through the heater element 31a, the heat from the heater element 31a causes the bi-metal motor 31 to warp upward, thus applying a lifting force on the valve stem 24 through an arm extension 31b arranged in cooperative relationship to a collar 32 affixed to the valve stem 24.

When the closing pull of the permanent magnet 29 is overcome by the bi-metal motor 31, the valve stem 24 moves upwardly with a positive snap-action. When the bi-metal motor 31 cools, the valve stem 24 carrying the collar 32 and the armature 30 will be forced downwardly. When the armature 30 is near the permanent magnet 29 it is pulled downward quickly so as to close the valve 14 with a snap action.

The operating mechanism of the main gas valve 14 may also be provided with a motor timing adjustment indicated generally by the reference numeral 33, the details of which are not necessary to the present invention.

It will be also apparent that a sleeve 34 may be provided in the upper portion of the operating mechanism for carrying a bushing 36 adapted to guide the valve stem 24 in its vertical reciprocatory movements.

A particular feature of the present invention resides in the provision of an interlocking switch structure indicated generally by the reference numeral 37 and adapted to be incorporated in the operating mechanism of the main gas valve 14. The interlocking switch structure 37 includes a pair of posts 38 which may be affixed to the housing 26 and upon which may be mounted a contact board 39 preferably made out of an electrically non-conductive insulating material. A lower switch contact 40 is provided on the contact board 39 and in the preferred embodiment herein shown preferably takes the form of a conventional button-type electrical contact which may be firmly affixed to the contact board 39.

An upper contact 41 is also provided which preferably takes the form of a flexible blade made of electrically conductive material and is mounted on a spacer 42 made of an electrically non-conductive insulating material carried by the contact board 39. The switch contact 41 is thus carried in spaced relationship to the lower switch contact 40 but, because of the inherent resilience of the flexible blade comprising the upper switch contact 41, the lower and upper switch contacts 40 and 41, respectively, will normally be in closed circuit position.

A tab 43 made of a suitable electrically non-conductive material is affixed to the free end of the flexible blade comprising the upper switch contact 41 and is arranged to lie in cooperative relationship between the circular ar-

mature 30 and the collar 32 affixed to the valve stem 24. When the valve stem 24 is actuated upwardly, the armature 30 will engagingly abut the tab 43 and flex the upper switch contact 41 upwardly, thereby breaking the electrical circuit connection between the upper switch contact 41 and the lower switch contact 40.

The contact board 39 is provided with a suitable lead terminal 44 which may be electrically connected to the lower switch contact 40 by means of an electrically conductive strip 46. A lead terminal 47 is also provided which may be electrically connected to upper switch contact 41 by means of a strip 48. A third terminal 49 is also provided and may be used to provide a connection for an electrical lead 50 associated with the bi-metal motor 31. The housing 26 may be provided with a suitable side aperture as at 51 to receive the electrical conduits which must enter the operating mechanism for electrical connection to the terminals 44, 47 and 49.

Referring again to Figure 1, the main gas valve 14 is shown in a circuit connection effecting a cooperative interlocked relationship with the oil valve 13.

In one particular type of installation which is herein described by way of illustrative example, an oil valve 13 is employed which preferably incorporates time delay characteristics in its operation, that is, it will not initiate the flow of an oil fuel medium to the combination gas and oil burner unit until a substantial predetermined interval of time has elapsed after its original energization and conversely, it will continue to supply an oil fuel medium to the combination gas and oil burner unit for a limited period of time after its deenergization. The electrically operated fuel oil valve 13 may constitute any one of several well known forms and for illustrative purposes has been shown as comprising a heater type valve including an electrical heater 13a. The valve 13 is further provided with a bimetallic element 13b which operates an actuating bar 13c when it is heated by the heater element 13a.

The actuating bar 13c is cooperatively associated with a pair of interlocking switches which are indicated generally at 52 and 53. The stem 13d of the valve 13 is arranged to actuate the elements aforementioned in a predetermined sequence, both upon the energization of the fuel oil valve 13 and upon the deenergization thereof.

As is schematically indicated on Figure 1, the desired sequence of operation is that a short time after the original energization of the heater element 13a, the actuating valve 13c effects the opening of the contacts of switch 52 and the closing of the contacts of switch 53. After a still further time interval, the actuating bar 13c engages the stem 13d of the valve 13 to open the valve 13 to permit fuel oil to be supplied to the combination gas and oil burner unit.

Upon deenergization of the heater element 13a, the sequence of operation reverses. The valve stem 13d is first released to its closed position and then after a predetermined time delay, the switch 53 is actuated to its open contact position while the switch 52 is actuated to its closed contact position.

By virtue of the provisions made in accordance with the present invention, the electrical control circuit between the fuel oil valve 13 and the main gas valve 14 is completely interlocked so irrespective of how one of the valves may have been opened, simultaneous operation by electrical

means of both the main gas valve 14 and the oil valve 13 is precluded.

For example, it may be noted that the vaporizer gas valve 12 and the blower motor 11 are concurrently energized by the closing of the normally opened contacts of the switch 53 subsequent to the energization of the heater coil 13a of the electrically operated oil valve 13. Hence, it is assured that the vaporizer gas valve 12 will be opened whereupon gas will be supplied to the vaporizer burner of the combination gas and oil burner unit to provide a suitable high temperature zone for vaporizing any fuel oil supplied through the oil valve 13 to the combination gas and oil burner unit. Simultaneous operation of the blower 10 will also be assured. The time delay incorporated in the mechanism of the electrically operated oil valve 13 insures that the oil will not be supplied to the high temperature zone of the combination gas and oil burner unit until proper combustion conditions are attained.

At the same time, the opening of the contacts of the normally closed switch 52, which will be seen to be connected in the energization circuit of the main gas valve 14, insures that the main gas valve 14 will remain deenergized and thus will be in its closed position. Accordingly, irrespective of other conditions in the circuit, the main gas valve 14 cannot be opened when the fuel oil valve 13 has been energized.

It should be further noted that if the oil valve 13 is operated manually, as might well occur under operating conditions subsequent to an electrical current interruption, or if the oil valve is jammed open because of mechanical difficulties, the valve stem 13d operates to open the switch 52, thereby breaking the electrical control circuit to the main gas valve 14.

Inasmuch as the contacts defined by the upper switch contact 41 and the lower switch contact 40, and electrically connected to the lead terminals 47 and 44, respectively, of the main gas valve 14, are connected in series circuit with the heater element 13a of the electrically operated fuel oil valve 13, the electrical control circuit between the fuel oil valve 13 and the main gas valve 14 is completely interlocked.

It may be noted that the provision of the interlocking switch structure contemplated by the present invention permits the effective utilization of additional safety devices in a control circuit similar to that adapted as in the present embodiment for a combination gas and oil burner unit. For example, a safety switch unit 54 may be associated with the blower 10 and connected in the energizing circuit of the heater element 13a of the electrically operated fuel oil valve 13. The switch 54 may be of well known construction and may be associated with the blower motor 11 in such a manner that as long as the motor is functioning normally, the contacts of the switch 54 will remain closed. However, when a failure of the blower motor 11 occurs, the switch 54 will open and will result in the deenergization of the heater coil 13a of the fuel oil valve 13 and hence a closing of the fuel oil valve 13.

The electrical control circuit may also be provided with a pilot flame responsive switch indicated generally by the reference numeral 56. The pilot flame switch operates in a conventional fashion to maintain a pair of switch contacts closed as long as the pilot flame for the combination gas and oil burner unit is burning and to open such contacts in the event of failure of the pilot flame produced by a pilot flame unit as-

sociated with the combination gas and oil burner unit. The contacts of the pilot flame switch 56 may be connected in the common leads included in the energizing circuits of both the fuel oil valve 13 and the main gas valve 14. Accordingly, upon the failure of the pilot flame, the pilot flame switch 56 will open its contacts and prevent the operation of either the fuel oil valve 13 or the main gas valve 14.

The cooperation of the outdoor thermostat 16 and the indoor thermostat 17 with the remaining elements of the control circuit is identical to that employed in my above referred copending application. When the outdoor temperatures are below a predetermined value, circuit connections are complete as illustrated in Figure 1 through the terminal O of the outdoor thermostat 16 to energize the heater element 13a of the electrically operated fuel oil valve 13 whenever the indoor thermostat 17 is calling for heat by closing of its contacts. When the outdoor temperature is above such predetermined value, the outdoor thermostat 16 completes an energization circuit through its contact G for the main gas valve 14 whenever the indoor thermostat 17 calls for heat by the closing of its contacts 17b.

From the foregoing description it will be apparent that the present invention provides an improved and simplified electrically operated valve construction employing an interlocking switch structure which makes such a valve adaptable for incorporation in an electrical control circuit incorporating several valves which must be operated in an interlocking relationship.

It will be understood, of course, that a person skilled in the art might suggest various minor modifications to the structure herein described by way of preferred embodiment and illustrative example only, however, I do not propose to be limited to the precise details herein set out for the sake of clarity but wish to embrace within the scope of this patent all such modifications as reasonably and properly fall within the scope of my contribution to the art.

I claim as my invention:

1. An interlocking switch arrangement for precluding simultaneous opening of electrically operated valves comprising, in combination, a first electrically operated plunger type valve, a second electrically operated plunger type valve, electrical operating means for each of said valves, a first electrical switch on said first electrically operated plunger type valve, a second electrical switch on said second electrically operated plunger type valve, said first switch including upper and lower switch contacts, at least one of said contacts comprising a flexible blade made of electrically conductive material so that the contacts may normally assume a closed circuit position, a tab of electrically non-conductive material disposed

on the end of the flexible blade switch contact whereby the flexible blade switch contact may be cooperatively associated with a portion of the plunger of said first valve for actuation thereby to an open position upon reciprocal movement of the valve plunger, lead terminals on said first switch electrically connected to said upper and lower switch contacts, said second switch including at least one pair of contacts normally biased to a closed contact position, means associated with the stem of said second valve to actuate said second switch contacts to an open position upon opening movement of said second valve stem, lead terminals electrically connected to said second switch contacts, and leads between the terminals on said first and second electrical switches in series connection with the electrical operating means of said first and second electrically operated valves, whereby said first and second electrical switches may be interlocked electrically to preclude simultaneous opening of said valves.

2. In a control system for a combined gas and oil burning heater of the type including a first electrically operated valve for controlling the supply of gas to the heater, a second electrically operated valve for controlling the supply of oil to the heater, a thermostat and circuit means controlled by the thermostat for selectively energizing the first or second valve, the improvement of an interlocking switch structure for the first electrically operated valve comprising a contact board, a first switch contact carried by said board, an insulating spacer on said board, a flexible switch contact blade carried by said spacer with a portion thereof normally contacting said first switch contact, a tab of electrically non-conductive material projecting from the free end of said blade into cooperative relationship with a portion of the stem of a valve and lead terminals on said contact board electrically connected to the switch contacts, whereby the interlocking switch structure may be electrically connected in said circuit means to preclude simultaneous electrical operation of the first and second electrical operated valves thereby insuring that only oil or only gas be supplied to the combined gas and oil burning heater.

CYRIL CHARLES YOUNG.
